UNITED STATES PATENT OFFICE.

THEODORE R. CAMERON, OF SAN ANTONIO, TEXAS.

MECHANICAL PACKER.

1,366,631.

Specification of Letters Patent. Patented Jan. 25, 1921.

Application filed April 9, 1919. Serial No. 288,736.

To all whom it may concern:

Be it known that I, THEODORE RAYMOND CAMERON, a citizen of the United States, residing at San Antonio, in the county of Bexar and State of Texas, have invented 5 certain new and useful Improvements in Mechanical Packers, of which the following is a specification.

My invention relates to mechanical packing apparatus, adapted to use in connection 10 with a power operated press, such as a cotton press, while not necessarily restricted to this use.

An important object of the invention is 15 to provide automatic means to cause the platen of the packer to reciprocate continuously during the operation of the apparatus, such means embodying a flexible element and a worm drum upon which the flexible 20 element is wound.

Other objects and advantages of the invention will be apparent during the course of the following description.

In the accompanying drawings, forming a 25 part of this specification and in which like numerals are employed to designate like parts throughout the same,

Figure 1 is a side elevation of the apparatus, embodying my invention,

Fig. 2 is a plan view of the same,

Fig. 3 is an end elevation of the same,

Fig. 4 is a perspective view of the belt shifting apparatus removed,

Fig. 5 is a longitudinal section through 35 one of the worm drums,

Fig. 6 is an enlarged detail section through the worm drum, taken on line 6—6 of Fig. 5, and,

Fig. 7 is a perspective view of lock means 40 for the rock-shaft.

In the drawings, wherein for the purpose of illustration is shown a preferred embodiment of my invention, a supporting frame is shown comprising longitudinal beams 10, 45 connected by transverse beams 11 and 12. The outer ends of the beams 10 are supported by vertical posts 13, while their inner ends are connected with a block 14, secured to the head platen 15 of the power press.

50 Secured to the rear beam 10 are vertical beams 16, to which is connected a guard 17, as shown.

Rigidly secured to the transverse beams 12, as shown in Fig. 1, are vertical guide sleeves 18, receiving ram-posts 19, adapted to reciprocate therein. At their upper ends, these ram-posts are connected with sockets or couplings 20, rigidly secured to a head-yoke 21. At their lower ends, the ram-posts 19 are secured to couplings 22, 60 rigidly secured to a platen 23, as shown. This platen is adapted to operate with a press box 24.

Connected with the transverse beams 11 and 12 are bearings 24, rotatably receiving 65 a horizontal shaft 25. This shaft has two worm drums 26, rigidly secured thereto. These worm drums have flexible elements, such as cables 27, wound thereon. The cable is anchored to each worm drum by depressing a portion, as shown in Figs. 6 and 7, 70 into a recess 27' formed in the worm drum, and passing a transverse pin 28 through the drum, outwardly of the depressed portion of the cable.

75 The lower ends of the cables are secured to attaching elements 29, pivoted to the ends of a horizontal equalizing bar 30, having an apertured head 31, formed between the ends thereof to loosely receive a pin 32, carried by the platen. The head 31 is arranged beneath and contacts with a compressible coil spring 33, contacting with the nut 34, carried by the pin 32. The function of the bar 30 is to maintain the cables 27 at the 80 same tension. The upper ends of the cables are connected with eye-bolts 35, operating through openings in the head-yoke 21. These eye-bolts have their upper ends screw-threaded and engaged by adjusting nuts 36, 85 as shown. It is thus seen that rotation of the worm drums will effect the longitudinal movement of the cables 27 which in turn will cause the platen 23 and associated elements 90 to be reciprocated.

95 The shaft 25 receives its rotation from a large gear 37, driven by a small gear 38, rigidly secured to a counter-shaft 39, journaled through stationary bearings 40, rigidly secured to the transverse beams 12.

100 The numeral 41 designates a tight pulley rigidly secured to the counter-shaft 39, and 42 and 43 are loose pulleys rotatable thereon. The numeral 44 designates an open belt, and

45 a crossed belt, these belts engaging a common driving pulley, not shown.

Means are provided to shift these belts 44 and 45, comprising shifting arms 46, having heads 47 to suitably receive the belts therein. These arms are rigidly secured to a horizontal reciprocating U-shaped frame 48, operating in stationary guides 49.

Arranged transversely of the platen 23 is a horizontal rock-shaft 50, journaled through bearings 51. This rock-shaft has an upstanding crank 52 (see Fig. 4) rigidly secured thereto, having pivotal connection with a link 53, pivoted to one side of the sliding frame 48. A lever 54 is pivotally mounted upon the rock shaft 50, and disposed near the crank 52. This lever carries a loop 55, extending upon opposite sides thereof, and loosely receiving the upper end 20 of the crank 52. In operation, when the shaft 50 is turned, the crank 52 will move the lever 54 past dead center, the lever then automatically swinging to the extreme position upon one side of dead center, thereby quickly 25 effecting the complete movement of the crank 52, the crank then engaging the end of the loop 55. This movement of the lever 54 is effected by a weight 56, rigidly secured to the same near its free end. A tappet arm 30 57 is also rigidly secured to the rock-shaft 50 and carries a roller 58, to be alternately engaged by upper and lower tappets 59 and 60, secured to the head-yoke 21 and platen 23, as shown.

35 A manually operated crank 61 is rigidly secured to one end of the rock shaft 50 and this crank is adapted to be held within a forked latch 62, rigidly secured to a rock-shaft 63, journaled through bearings 64. 40 This rock shaft is turned by a crank 65. When the rock-shaft 50 is turned by means of the crank 61 so that it assumes the intermediate position, the belts 44 and 45 will be shifted to the loose pulleys 42 and 43, 45 whereby the machine will be stopped, the crank 61 being then held within the forked latch 62.

The operation of the apparatus is as follows:

50 With the belts in the position shown in Fig. 1, the open belt 44 may be assumed to be driving the fast pulley 41, in the direction of its arrow. As viewed in Fig. 3 the shaft 25 will then be rotated counter-clockwise. 55 This counter-clockwise rotation of the shaft 25 will cause the worm drums 26 to rotate in the same direction, whereby the platen 23 will be elevated. This upward movement of the platen continues until the lower tappet 60 engages the tappet arm 57, swinging the same upwardly. This movement of the tappet arm turns the rock-shaft 50, until the crank 52 swings the lever 54 past dead center, this lever then quickly comple-

ing the turning movement of the rock-shaft. 65 When the crank 52 moves forwardly sufficiently, the open belt 44 is shifted to the loose pulley 42, while the crossed belt 45 will engage the fast pulley 41. It is thus seen that the rotation of the shaft 25 will be 70 reversed, and the platen will move downwardly until the tappet 59 engages the tappet arm 57, to turn the rock-shaft 50 in an opposite direction. When this rock shaft is turned sufficiently, the belts are again 75 shifted whereby the open belt engages the fast pulley and the crossed belt the inner loose pulley 43, the platen again rising. This operation is continued automatically 80 until both belts are shifted upon the loose pulleys, which is accomplished by swinging the crank 61 to the intermediate position. This crank may be locked in this position by engagement with the latch 62, as above stated.

85 In this disclosure I have shown an advantageous embodiment of my invention, but it is apparent that certain changes in the detailed construction may be resorted to without departing from the spirit of the 90 invention or the scope of the appended claims.

Having thus described my invention, I claim:

1. A power reversing mechanism, comprising an operating shaft, a movable member, means driven by the shaft to effect vertical reciprocating movement of the movable member, means to drive the operating shaft including fast and loose pulleys, open and crossed belts to engage the pulleys, belt shifting means engaging said belts, said means comprising shifting arms, a slideable frame connected thereto, a rock-shaft connected to said slideable frame, and means 105 carried by the movable member to actuate said shaft.

2. A power reversing mechanism, comprising an operating shaft, a movable member, means driven by the shaft to effect vertical reciprocating movement of the movable member, means to drive the operating shaft including fast and loose pulleys, open and crossed belts to engage the pulleys, belt shifting means engaging said belts, said means comprising shifting arms, a slideable frame connected thereto, a rock-shaft connected to said slideable frame, a tappet lever mounted on said rock-shaft, and means carried by said movable member and engaging said tappet 120 lever to actuate said shaft.

3. A power reversing mechanism for packers comprising a platen, an operating shaft, means driven by the shaft to effect an up and down movement of the platen, means 125 to drive the operating shaft including fast and loose pulleys, open and crossed belts to engage the pulleys, a belt shifting device

engaging the belts, a rock-shaft arranged near the platen, a crank rigidly secured to the rock-shaft, a link connecting the crank and the belt shifting device, a lever provided 5 with a weight and pivoted upon the rock shaft, a loop carried by the lever and receiving the crank, a tappet arm rigidly secured to the rock-shaft to turn it, and tappets

connected with the platen to engage and shift the tappet arm. ¹⁰

In testimony whereof I affix my signature in presence of two witnesses.

THEODORE R. CAMERON.
